(No Model.)

W. BURNHAM.

WATER RETURNING APPLIANCE FOR STEAM GENERATORS.

No. 394,830.

Patented Dec. 18, 1888.

UNITED STATES PATENT OFFICE.

WALTER BURNHAM, OF CHICAGO, ILLINOIS.

WATER-RETURNING APPLIANCE FOR STEAM-GENERATORS.

SPECIFICATION forming part of Letters Patent No. 394,830, dated December 18, 1888.

Application filed February 21, 1888. Serial No. 264,814. (No model.)

To all whom it may concern:

Be it known that I, WALTER BURNHAM, of Chicago, in the county of Cook and State of Illinois, have invented certain new and useful 5 Improvements in Water-Returning Appliances for Steam-Generators; and I do hereby declare that the following is a full, clear, and exact description thereof, reference being had to the accompanying drawings, and to the letters of reference marked thereon, which form a part of this specification.

This invention relates to means for maintaining a movement of steam through a return-pipe or water-lifting pipe connected at 15 its receiving end with a steam-pipe and provided at its delivery end with a water-column or other obstruction which permits outflow of water therefrom.

The immediate object of the invention is to 20 automatically control the relative pressure in the low-pressure space of the return-pipe, whereby the steam-flow is induced.

The invention is here diagrammatically illustrated in Figure 1 in connection with a 25 steam-generator and steam-pipe leading therefrom to a point below the water-level of the generator, where it is connected with a separator and a return-pipe leading from the separator upward to a point above the generator, 30 and thence descending into the water-space of the generator. The vertical distance of such descent is sufficient to accommodate in the descending leg of the pipe a water-column of height due to the difference in pressure 35 between the generator and the low-pressure space in the pipe above the water-column, the reduction of pressure in which space it is the purpose of this invention to more perfectly regulate and more reliably maintain. This 40 arrangement of generator, steam-pipe, separator, and return-pipe is generally that which is shown in an application for patent filed by William Irving, of Chicago, on February 7, 1888, Serial No. 263,225, and the operation of 45 which, as set forth by him, is to give a steam-flow through the return-pipe from its connection with the steam pipe or separator to the upper part of the descending leg of said return-pipe, by which steam-flow water in detached masses is swept from the steam pipe 50 or separator into the descending leg of the return-pipe, whence it falls into the generator.

The action of this circuit, as above set forth, is the result of a lower pressure in the upper part of the descending leg of the return-pipe than 55 that which subsists in the steam-pipe at its connection with the return-pipe. It is the purpose of this invention to automatically and certainly insure a difference between the pressure in said low-pressure chamber and that in the 60 steam-pipe, in order that a flow of steam may be maintained through the return-pipe possessing a degree of force adequate to the performance of all the work which said return-pipe may be under the circumstances called 65 upon to perform.

To this end the invention consists, primarily, in providing the low-pressure space or chamber of the return pipe or system with an automatically-regulated escape, and, secondarily, in the combination, with the return-pipe 70 or low-pressure chamber of the circuit, of a regulated escape mechanism adapted to insure a prescribed reduction of pressure.

Referring to the accompanying drawings 75 for a more full statement of the invention, Figure 1 is a transverse section of a steam-generator and a diagrammatic view of two pipe-circuits connected therewith and containing the invention. Fig. 2 is a vertical central 80 section of one of the automatic escape-valves seen in Fig. 1.

A represents a generator; B, a steam-pipe leading therefrom.

C is a separator connected in the steam-pipe, and D is a return-pipe taking steam and water from the separator C and delivering water into the generator A through a descending terminal leg, D', which contains a water-column of such height above the water-line of 90 the generator as is due to the difference between the pressure in the generator and that in the return-pipe D above said water column. Above the water column on the leg of the return-pipe D is a space of lower pressure than 95 any other part of the circuit, because most remote from the source from which steam is supplied thereto, and therefore subject to less temperature than other parts of the circuit. Said Irving has already provided for 100 establishing a lower pressure in such portion of the return-pipe than would be attained by more radiation or condensation by means of a valved escape-pipe, d, such escape being

subject to control by hand alone. The object of the valved escape-pipe d is to afford a bodily outlet for steam or steam and water from the return-pipe D, and thus to promote 5 a more active flow of steam from the steam-pipe B toward this point of escape or low pressure.

For the attainment of my purpose I provide an escape-passage leading from the low-pressure 10 chamber of the return-pipe, which is subject to automatic control. Two forms of such device are shown having certain general characteristics in common, and one having special features of construction and operation which 15 give it certain advantages over the other for particular situations and circumstances. One of these devices, E, is an ordinary safety-valve weighted or adjusted to yield and permit an outflow of steam when subject to a given 20 interior pressure. Applied to the low-pressure chamber or space of a return-pipe, as shown, such a valve insures that a pressure in said low-pressure chamber shall not exceed a given degree to which the safety-valve is set to discharge. This form of regulated 25 escape for said low-pressure chamber will be useful to those systems in which the generator and steam-pipe are subject to a uniform or practically uniform pressure, and the 30 difference between the pressure of the generator or the pressure of the steam-pipe at its junction with the return-pipe and that of the low-pressure chamber in the return-pipe will in such a case be sufficiently regulated for all 35 practical purposes by adjusting the safety-valve to open at a prescribed degree less than that of the generator and the steam-pipe.

F is an escape-valve of peculiar construction. (Seen in side view in Fig. 1 and illustrated in detail by the enlarged vertical central section of Fig. 2.) As will be seen by this figure, the shell of the valve F is provided with two chambers, $f f'$, the former of which is connected by the pipe d' with the 40 low-pressure chamber of the return-pipe D. The chambers $f f'$ communicate with each other through two openings, $f^2 f^3$, one above the other, after the manner of other well-known valves of the balanced order. The 45 valves $F' F^2$, which fit the ports $f^2 f^3$, are connected on a stem, F^3 , which passes through the cap f^4 and supports the weight-arm F^4 . Below the cap f^4 the bulb or shell of the valve is provided with a neck, F^5 , having an interior cylindric passage, to which is fitted a disk or piston, F^6 , secured to the valve-stem F^3 . The passage for the valve-stem through the cap of the valve-shell is sufficiently free to allow air to enter and any steam to escape 50 into the atmosphere which shall pass the piston F^6 . The outer chamber, f' , of the bulb or case is provided with a discharge-orifice, f^5 , provided with a valve, f^6 .

In the operation of this device, when the 55 pressure in the low-pressure chamber of the return-pipe is below the degree desired, the valve-stem F^3 , with its valves F' and F^2

and piston F^6 , will be depressed, giving an outflow of steam through the passages $f^2 f^3$ into the chamber F' . When the pressure in this chamber f' reaches a prescribed degree, (as, for example, two pounds,) the steam in this outer chamber, acting on the piston F^6 , raises the valves $F' F^2$, cutting off further outflow of steam until the pressure in f' shall have 70 been reduced by escape through the orifice f^5 below the prescribed degree, when the valves $F' F^2$ are again opened and give a further outflow of steam from the low-pressure chamber. The cock f^6 may be turned to give any 75 desired capacity to the orifice f^5 , and the valves $F' F^2$ in effect limit the pressure of steam in the chamber f' , from which the orifice f^5 is the escape. There is always thus an 80 escape of steam from the low-pressure chamber of the return-pipe D, to which the valve F is attached, equal to what will flow through an orifice, f^5 , under a practically fixed pressure of two pounds. The escape is therefore 85 substantially uniform, and there will be, consequently, a practically constant reduction of 90 the pressure in the low-pressure chamber of the return-pipe from or below that in the steam pipe or generator. Under these 95 circumstances the water-lifting force of the return-pipe will be practically uniform without respect to variations of pressure in the steam-pipe and generator, provided only that such 100 pressure in the steam pipe or separator be high enough to raise the piston F^6 against the weight on the arm F^4 . A flexible diaphragm 105 may obviously be substituted for the piston F^6 .

It is to be understood that the pipe D, herein generally called the "return-pipe," may deliver into any other receptacle than a 110 generator, and may be provided with a water column other than one forming part of the same body of water with that in the generator or receptacle, and that, in fact, it may be provided with any other suitable form of obstruction 115 adapted to give passage to water in place of a water column.

In other applications for patent filed by me of even date herewith I have fully shown and described other constructions for a water 115 column which may be substituted in place of the direct connection of the return-pipe with the water-space of the generator herein illustrated, and also constructions by which a suitable obstruction is provided in the pipe D in 120 place of the water column.

I claim as my invention—

1. The combination, with a generator, a steam-pipe leading therefrom, and a pipe taking both steam and water from the steam-pipe, and having an obstruction at its opposite end adapted to give outflow of water, of an automatic escape-valve giving discharge from the low-pressure chamber of said obstructed pipe, substantially as described. 130

2. The combination, with a generator, a steam-pipe leading therefrom, a separator connected with the steam-pipe, and a pipe taking both steam and water from the separator,

terminating in the generator and containing a water column at its delivering end, of an automatic escape-valve giving steam-discharge from the low-pressure space of said last-mentioned pipe, substantially as described.

3. The combination, with the pipe D of a pipe system of the general character described, of a double-chambered escape-valve, F, having one of its chambers connected with the low-pressure space in the pipe D and the other chamber provided with a valved outlet, and also having a valved passage leading from one chamber to the other and controlled by the pressure in the chamber having the valved outlet, substantially as described.

4. The combination, with the pipe D, of a valve, F, provided with chambers $f'f'$, connected by passages f^2f^3 , a valved orifice, f^5 , leading from the chamber f' , a weighted rod provided with valves F' and F^2 , fitted to the 20 passages f^2f^3 , and a piston or disk, F^6 , exposed on one side to pressure in the chamber f' and on the other side to the atmosphere.

In testimony that I claim the foregoing as my invention I affix my signature in presence 25 of two witnesses.

WALTER BURNHAM.
